ICE TRAY GRID

Arthur J. Frei and Raymond C. Davis, Dayton, Ohio,
assignors to General Motors Corporation, Detroit,
Mich., a corporation of Delaware

Application June 24, 1957, Serial No. 46,711

Term of patent 14 years

(Cl. D67—3)

Figure 1 is a perspective view of the ice tray grid showing our new design;

Figure 2 is another perspective view of the ice tray grid taken from the end and side thereof opposite that shown in Figure 1;

Figure 3 is an end view of the grid opposite the end thereof shown in Figure 1; and

Figure 4 is a top view of one of the transverse walls of the grid.

The dominant feature of the design resides in the curvature of the grid walls.

We claim:

The ornamental design for an ice tray grid, as shown and described.
